UNITED STATES PATENT OFFICE.

HARVEY BIRCHARD TAYLOR, OF PHILADELPHIA, PENNSYLVANIA, ASSIGNOR TO WILLIAM CRAMP & SONS SHIP & ENGINE BUILDING COMPANY, A CORPORATION OF PENNSYLVANIA.

HYDRAULIC TURBINE.

Original application filed July 24, 1917, Serial No. 182,498. Divided and this application filed May 23, 1922. Serial No. 562,970.

To all whom it may concern:

Be it known that I, HARVEY BIRCHARD TAYLOR, a citizen of the United States, residing at Philadelphia, in the county of Philadelphia and State of Pennsylvania, have invented certain new and useful Improvements in Hydraulic Turbines, of which the following is a specification.

The principal object of my invention is to provide a new and improved substructure for a hydraulic turbine of the inflow type and particularly to such a turbine having a straight draft tube receiving the discharge from the runner and discharging it through an annular outlet at its lower end. Another object of my invention is to provide suitable supporting means for such a turbine and its associated masonry structure. Another object is to make a stay vane ring to go in the draft conduit of such a turbine. Still another object of my invention is to provide columns or piers in the draft conduit beneath such a turbine that shall be effective as supports for the superposed structure and at the same time have the proper disposition as vanes with respect to the water flow in the conduit. These and other objects of my invention will be made apparent in the following disclosure of a limited number of examples of forms in which the invention may be embodied.

In the accompanying drawings illustrating the invention,

Figs. 1 and 2 are vertical and horizontal sectional views respectively of a turbine structure embodying the invention.

The turbine runner 12 has vanes 11 and is of the vertical shaft type. The supply conduit terminates in a spiral or volute portion 14 surrounding the runner 12. A speed ring 15 is provided directing the flow to the adjustable guide vanes 16 so that the entering flow has a whirl imparted to it around the axis of the runner as a center.

Directly below the runner 12 there is an ordinary straight draft tube 17 with vertical axis. Below this is a stay vane ring hav-

ing the vanes 18 extending across the annular flaring conduit between the crown ring 19 and the conical projection 20. The surfaces of the crown ring 19 and conical projection 20 are surfaces of revolution forming between them a flaring passage 21 receiving the flow in substantially axial direction from the straight draft tube 17 and turning it outward to the radial or horizontal direction and at the same time lowering both the meridian and whirling velocity components and thus acting as a diffuser to create a suction or draft lowering the back pressure on the draft tube 17.

The projection 20 extends upward from the horizontal floor 22 of the discharge conduit 23 as shown in Fig. 1 and finally curving and merging into the surface of this floor as indicated at 24. The center of this projection 20 is not carried up to a sharp point but is rounded off at its apex as indicated at 25 and it terminates below the horizontal plane of the crown ring 19. The annular space 27 between the end of the crown ring and the surface of the projection 20 forms an annular outlet from the draft tube 17, the lower wall of this annular outlet curving downward while the upper wall turns upward as indicated at 28, said walls at any point being spaced apart a distance less than the smallest diameter of the upper wall. The discharge conduit 23 has its vertical wall 30 in volute or spiral form beginning at the stay vane 18' and extending around to merge with the wall of the outlet passage 31 which leads to the tailwater and opens below the surface of the tailwater. While the diverging surfaces at 20, 28, permit the discharge to expand in a vertical direction the spiral wall 30 collects the flow lines into a solid stream directed outward through the outlet 31.

The meridian components of the velocity of the discharge are decelerated in the expanding draft tube 17, and in the annular outlet passage 21 both the meridian and whirling components of the flow are de-

celerated, the stay vanes 18 being designed to assist in the hydraulic operation of gradually reducing the velocity of the water while flowing between the vanes. For this purpose, they are suitably curved to receive the water in its natural direction of flow and to provide a gradually increasing cross sectional area measured perpendicularly to the stream elements between neighboring vanes. This deceleration of the outflow is continued in the expanding volute collector passage 23 so that all portions of the outflow conduit combine to convert the velocity head of the discharge into pressure head relieving the back pressure on the runner. These successive portions of the draft conduit merge smoothly and gradually into each other so that there are no abrupt changes in direction or velocity of the flow. The construction as a whole is simple and readily adapted to various installations by varying the proportionate length of the straight draft tube 17 and the sizes and proportions of the remaining elements. The ring of stay vanes 18 directly supports the sub-structure masonry from the foundation below giving a continuous columnar reinforcement from the foundation all the way to the runner chamber. The core 20 with its rounded surface is formed directly in the concrete without the necessity of providing a metal tip or a cap piece.

I claim:—

1. A draft tube for a turbine comprising a straight expanding passage adapted to decelerate the discharge, and an annular passage receiving the flow from said straight passage and guiding it toward the radial direction while decelerating both the meridian and whirling components of velocity of flow, said annular passage being contained between outer surfaces of revolution and a central conical member having a convex rounded apex.

2. A draft tube for a turbine comprising a straight expanding passage adapted to decelerate the discharge, and an annular passage receiving the flow from said straight passage and guiding it toward the radial direction while decelerating both the meridian and whirling components of velocity of flow, said annular passage being contained between outer surfaces of revolution and a central conical member having a convex rounded apex and inclined surrounding surfaces extending outward beyond said surfaces of revolution.

3. A draft tube for a turbine comprising a straight expanding passage adapted to decelerate the discharge, an annular passage receiving the flow from said straight passage and guiding it toward the radial direction while decelerating both the meridian and whirling components of velocity of flow, said annular passage being contained

between outer surfaces of revolution and a central conical member having a convex rounded apex, and a stay vane ring extending between said surfaces of revolution and said conical member.

4. A draft tube for a turbine comprising a straight expanding passage adapted to decelerate the discharge, an annular passage receiving the flow from said straight passage and guiding it toward the radial direction while decelerating both the meridian and whirling components of velocity of flow, said annular passage being contained between outer surfaces of revolution and a central conical member having a convex rounded apex and inclined surrounding surfaces extending outward beyond said surfaces of revolution, and a stay vane ring extending between said surfaces of revolution and said conical member.

5. A draft tube for a turbine comprising a straight expanding passage adapted to decelerate the discharge, an annular passage receiving the flow from said straight passage and guiding it toward the radial direction while decelerating both the meridian and whirling components of velocity of flow, said annular passage being contained between outer surfaces of revolution and a central conical member having a convex rounded apex, and a volute collecting chamber receiving the flow from said annular passage and having upper and lower diverging walls and a surrounding spiral wall.

6. In a draft tube a flaring annular passage discharging the flow outwardly, and a volute collection chamber surrounding said passage and comprising upper and lower walls diverging away from each other in an outward direction and a surrounding spiral wall.

7. A draft tube passage for a turbine comprising an upper surface of revolution curving first downward and then upward and a lower surface of revolution having a downward inclination and forming with said upper surface of revolution an annular flaring passage turning the flow outwardly and decelerating its meridian and whirling components.

8. A draft tube passage for a turbine comprising an upper surface of revolution curving first downward and then upward and a lower surface of revolution having a downward inclination and forming with said upper surface of revolution an annular flaring passage turning the flow outwardly and decelerating its meridian and whirling components, and supporting stay vanes extending between said lower and upper surfaces.

9. A draft tube for a turbine, comprising a straight, gradually enlarging conical passage, a flaring annular passage receiving the flow from said conical passage and discharg-

ing it outwardly away from the turbine axis, and a volute collection chamber surrounding said annular passage adapted to gather together the diverging streams leaving said 5 annular passage and to discharge the flow in an integral stream having a direction tangent to said spiral.

10. A draft tube for a turbine, comprising a straight, gradually enlarging conical passage, a central concrete core, a flaring annular passage surrounding said central core and receiving the flow from said conical passage and discharging it outwardly away from the turbine axis, and a volute 15 collection chamber surrounding said annular passage adapted to gather together the diverging streams leaving said annular passage and to discharge the flow in an integral stream having a direction tangent to said 20 spiral.

11. In combination, a turbine runner with vertical axis, a masonry foundation structure below the runner having a downward flaring draft tube therein with a rounded 25 core and an annular discharge space, the discharge being of less area than an intermediate cross section measured normally to the lines of flow, and a series of metal stay vanes standing across said discharge space 30 around the axis with their upper ends engaging the masonry structure around said draft tube.

12. In combination, a turbine runner with vertical axis, a masonry foundation structure below the runner having a downward flaring draft tube therein with a curved conical wall and an annular discharge space, the discharge space being of less area than 35 an intermediate cross-section measured normally to the lines of flow, said masonry foundation structure comprising a wall extending across below said draft tube and having a central upwardly projecting rounded portion, and a series of metal stay vanes 40 standing on said wall around the axis with their upper ends engaging the masonry structure thereabove.

13. In a turbine having a substantially axial discharge from the runner the combination with an expanding draft tube having 45 its end curving outward toward tailwater and adapted to discharge the flow toward tailwater and outwardly on each side of said expanding tube, of a passage on each side receiving and collecting said side flow and having an upper surface continuous with and curving upward from the flaring end surface of said expanding draft tube, said 50 passage collecting and guiding the flow toward tailwater while decelerating its velocity.

14. In a turbine having a substantially axial discharge from the runner the combination with an expanding draft tube having 55 its end curving outward toward tail-

water and adapted to discharge the flow toward tailwater and outwardly on each side of said expanding tube, of a passage on each side receiving and collecting said side flow and having an upper surface continuous with and curving upward from the flaring end surface of said expanding draft tube, said 70 passage collecting and guiding the flow toward tailwater while decelerating its velocity, and a central conical member cooperating with the flaring end surface of said expanding draft tube to spread the flow outward on each side.

15. In a hydraulic turbine the combination with a straight downwardly directed draft tube, of a flaring portion at its lower end turning the flow and discharging it outwardly, and a discharge passage receiving the flow from said flaring portion and extending in unsymmetrical form around the outlet of 80 said flaring portion and offset laterally on one side so as to receive and collect and decelerate a whirling outflow while turning it and guiding it toward final tailwater.

16. In a hydraulic turbine the combination with a straight downwardly directed draft tube, of a flaring portion at its lower end turning the flow and discharging it outwardly, and a discharge passage receiving the flow from said flaring portion and extending in unsymmetrical form around the outlet of 90 said flaring portion and offset laterally on one side so as to receive and collect and decelerate a whirling outflow while turning it and guiding it toward final tailwater, the upper wall of said discharge passage turning upward from said flared portion.

17. In a hydraulic turbine the combination with a straight downwardly directed draft tube, of a flaring portion at its lower end turning the flow and discharging it outwardly, and a volute discharge passage receiving the flow from said flaring portion and extending in unsymmetrical form 100 around the outlet of said flaring portion and offset laterally on one side so as to receive and collect and decelerate a whirling outflow while turning it and guiding it toward final tailwater.

18. In a draft tube for a hydraulic turbine the combination with a straight portion receiving the flow from the runner, of an outwardly flaring conduit at the outlet end of said straight portion and comprising upper and lower walls curving outward away from the axis toward a radial direction, said walls at any point being spaced apart a distance less than the smallest diameter of said upper wall, and a discharge passage surrounding said flaring portion and having its upper surface formed as a continuation of the upper surface of said flaring portion.

19. In a draft tube for a hydraulic tur-

bine the combination with a straight portion receiving the flow from the runner, of an outwardly flaring conduit at the outlet end of said straight portion and comprising upper and lower walls curving outward away from the axis toward a radial direction, the lower wall at its uppermost point being

spaced below the lowermost flare of the upper wall, and a discharge passage surrounding said flaring portion and having its upper surface continuing from the upper surface of said flaring portion. 10

HARVEY BIRCHARD TAYLOR.
